DROP LEAF EXTENSION TABLE

John O. Van Koert, New York, N. Y., assignor to Drexel
Furniture Company, Drexel, N. C., a corporation of Delaware

Application August 2, 1955, Serial No. 37,267

Term of patent 7 years

(Cl. D33—14)

I claim:

The ornamental design for a drop leaf extension table, as shown.
